E. KIRKBRIDE,
RIBBON INKING MACHINE,
APPLICATION FILED MAY 7, 1918.

Patented July 22, 1919.

2 SHEETS—SHEET 2.

UNITED STATES PATENT OFFICE.

EDMUND KIRKBRIDE, OF CAMDEN, NEW JERSEY, ASSIGNOR TO TYBON COMPANY, OF WILMINGTON, DELAWARE, A CORPORATION OF DELAWARE.

RIBBON-INKING MACHINE.

1,310,625.

Specification of Letters Patent. Patented July 22, 1919.

Application filed May 7, 1918. Serial No. 233,070.

To all whom it may concern:

Be it known that I, EDMUND KIRKBRIDE, a citizen of the United States, residing at Camden, in the county of Camden and State 5 of New Jersey, have invented a certain new and useful Ribbon-Inking Machine, of which the following is a specification.

My invention relates to a machine for inking or re-inking ribbons, intended particularly for typewriter use.

The purpose of my invention is to simplify the construction, facilitate the application of the ink and improve the operation, particularly for use by amateurs, at the 15 same time that the risk of soiling the hands or person of the user is much reduced.

A further purpose is to provide a simple and effective guide for the ribbon within the inking bath which can readily be lifted 20 when it is desired to pass the ribbon through the bath.

A further purpose is to provide for a spool wind corresponding in angular speed to that for winding the ribbon upon the 25 smallest part of the spool or in excess thereof and providing a slip between it and the spool, to take care of the slip due to increasing diameter of the ribbon body upon the spool.

Further purposes will appear in the specification and in the claims thereof.

I have preferred to illustrate my invention by but one form, selecting therefor a form which is simple, inexpensive and 35 highly efficient and which at the same time well illustrates the principles of my invention.

Figure 1 is a top plan view of my preferred form, the cover being sectioned.

Fig. 2 is a vertical longitudinal section of Fig. 1 upon line 2—2.

Figs. 3 and 4 are sections of Fig. 2 taken upon line 3—3 and 4—4 respectively.

Fig. 5 is a side elevation of my preferred 45 form.

In the drawing similar numerals indicate corresponding parts.

The manufacture as well as the re-inking of typewriter ribbons is largely in the hands 50 of a very few large manufacturers. Not only small users but concerns using thousands of typewriter ribbons yearly are forced to buy from them.

With the larger users, this is due largely 55 to the lack of a suitable inking machine

simple enough to permit use by a comparative amateur and effective enough to give results comparable with those to be obtained by a good manufacturer. Though the ribbon material can be obtained in bulk at a 60 very low price and the cost of the ink required per ribbon is small, a high price has been maintained for the ribbons.

My invention is designed primarily to enable users of ribbons in quantity to ink or 65 re-ink them for their own use.

The frame 1 is shown as mounted upon legs 2 and provided with a cover 3. It carries side frame members in the form of supporting brackets such as shown at 4 and 70 5 for a web spool 6 in bearings 7; bearings for the shaft 8 of roller ribbon guide 9; a ribbon guide 10 in the form of a yoke whose arms 10', 10² are movable in slots 11 and secured therein by thumb screws 12; rolls 75 13 and 14 rotatable on shafts 15 and 16; suitable connecting gearing; and spindle winding mechanism driven thereby for turning the ribbon spool 17.

When the machine is used to ink new 80 typewriter ribbons the spool 6 is intended to carry a web of white ribbon tape 18, preferably long enough to make a number of the finished ribbons; when used for re-inking, the old ribbon is placed upon it. 85

The ribbon 18 passes from the spool over the guide 9 and thence over a roller 19 which is shown in the figures as depressed to carry the ribbon down beneath the surface of the ink in an ink tank 20 beneath the body of the machine. When the ribbon is first fed through the machine the roller 19 is located above the ink level 20 in the ink well so that the ribbon may be passed beneath it reliably and accurately without dipping the fingers into the ink, and the ribbon-carrying guide roller is then moved down to the position shown and secured by the thumb nuts 12 at opposite sides. The height adjustment is made by movement of 100 the yoke in the slots 11.

The rollers 13 and 14 are of steel and the upper roller 13 is pressed downwardly against the lower roller by means of screws 21 passing through plates 22 held to the 105 frame by screws 23 and pressing against the roll boxes 24 as seen in Figs. 2 and 3.

The rolls are turned by a handle 25 connected with one of them. They are shown of different length, the roll 14 being shorter 110

than the roll 13 as a convenient means of causing any ink which spreads toward the edges of either roll to drip from the lower roll into the ink tank. The roll 14 is connected by gears 26, 27 and 28 with a spindle 29 which may be adjustable axially to suit different widths of ribbon spool. This may be accomplished by placing the pins 30, 31 in different openings in the spindle. The 10 spindle is keyed to the gear 28.

The gears are so proportioned that the peripheral speed of the spool core or bottom shall be at least equal to the peripheral speed of rolls 13 and 14, so that the ribbon 15 18 may be maintained under tension at all times between, but permitting slip between the driving spindle 29 and the ribbon spool 17.

The spindles 32 and 33 are both axially 20 movable to permit insertion of the two spools and are resiliently pressed against them by springs 34 and 35 bearing axially upon the spindles at one end, 36 and 37 and upon fixed parts 38 and 39 at the other.

25 The ink tank is preferably inserted laterally within a compartment closed by door 40 and secured by fastener 41.

In operation for inking a new ribbon, a 30 roll of ribbon fabric, web or braid, preferably long enough for a number of ribbons, is wound upon spool 6 and the end passed over roll 9 below roll 19 when it is in raised position, through between rolls 13 and 14 and thence to winding position upon the 35 typewriter spool 17. The yoke 10 is then lowered to force the ribbon at this point below the surface of the ink. The rolls are then operated passing the ribbon through between them and on to the spool. When 40 the operation is first begun the connection with the ribbon spool 17 is not made until inked ribbon of sufficient length for this purpose has passed through between the rolls.

45 The ink used for the purpose is thick enough not to pour and might more properly be called a paste than a liquid. Consequently it is necessary to have it squeezed into the web, which is done by the pressure

rolls, at the same time they squeeze the excess from the web and whatever excess travels toward the edges of the rolls is ultimately dropped from the edge of the shorter roll to fall into the tank.

Where a typewriter ribbon is to be re- 55 inked, the dirt in it should be thoroughly removed. The dried ribbon is then treated in the same general way as the new ribbon web is treated in the operation of inking a new ribbon.

Having described my invention what I claim as new and desire to secure by Letters Patent is:

1. In a ribbon-inking machine, a reel for the web and ink squeezing rolls in combination with an ink container, a yoke adapted to guide the web between the spool and rolls and means for securing the side arms of the yoke at different heights to guide the web above or below the surface of the ink 70 as desired.

2. In a ribbon-inking machine, a reel for the web, pressure rolls for the web, an ink container and a yoke adapted in non-use to be secured above the ink and in use to act 75 as a guide for the web below the surface of the ink.

3. In a ribbon-inking machine, a reel for the web, supports therefor, web squeezing rolls, a supply of ink for the web and a vertically adjustable guide adapted to depress 80 the web beneath the surface of the ink and guide it therein.

4. In a ribbon-inking machine, a reel for the web, squeezing rolls for the web, a supply of ink for the web, a frame having slots on opposite sides of the ink supply, a yoke adapted to pass through said slots and having the middle of the yoke formed as a guide for the web and retaining means for holding the yoke at different heights within 90 said slots to permit passage of the web between the yoke and ink or force the ribbon beneath the surface of the ink as desired.

EDMUND KIRKBRIDE.

Witness:

WM. STEELL JACKSON.
